AIR TURBINE CARBURETOR

William O. Haddock, Los Angeles, Calif.

Application February 10, 1937, Serial No. 125,689
Renewed June 9, 1939

5 Claims. (Cl. 261—83)

My invention relates to the carburetion of liquid fuel for internal combustion engines.

In spite of the many developments of internal combustion engines during the past generation, particularly in the automotive field, the efficiency of consumption of fuel by these engines is still relatively low.

It is an object of my invention to provide a carburetor for internal combustion engines which will perceptibly increase the efficiency of fuel consumption by these engines.

Many efforts have been made in the past to provide a carburetor which will prepare low grade fuel so that this may be satisfactorily used with high compression internal combustion engines of the type employed in automobiles and airplanes. These efforts have not hitherto been successful, and the only fuels which may be satisfactorily used in these engines with the types of carburetors available prior to my invention have been high gravity blends of gasoline.

It is another object of my invention to provide a carburetor which is adapted for use on high compression internal combustion engines, such as those used in automobiles and airplanes, and which will permit the satisfactory use of low grade fuels in the operation of these engines.

One of the difficulties inherent in the carburetors formerly in general use was the failure of these carburetors to completely break up the liquid fuel into a vapor prior to delivering this to the engine.

It is an object of my invention to provide a carburetor which will form a substantially homogeneous mixture of liquid fuel with air and deliver this mixture to an internal combustion engine.

The means of accomplishing the foregoing objects, as well as further objects and advantages, will be more fully set forth in the following description taken in connection with the accompanying drawings, in which:

Fig. 1 is a vertical sectional view through a preferred embodiment of my invention;

Fig. 2 is a side elevational view of the rotor mandrel of my invention, with upper and lower rotors mounted thereon;

Fig. 3 is a horizontal sectional view taken on the line 3—3 of Fig. 1 and illustrating the volute of my carburetor;

Fig. 4 is a horizontal sectional view taken on the line 4—4 of Fig. 1, and illustrates the pounding block which constitutes the upper wall of the centrifugal chamber formed within the volute;

Fig. 5 is a horizontal sectional view, taken on the line 5—5 of Fig. 2 and showing the conformation of the blades on the upper rotor of my carburetor;

Fig. 6 is a horizontal sectional view taken on the line 6—6 of Fig. 2 and illustrating the construction of one of the sectional baffle screens used on the rotors of my invention.

Referring now specifically to the drawings, I have shown therein a carburetor 10, comprising a preferred embodiment of my invention, this including a fuel cup 11 providing therein a float chamber 12 which is kept filled with liquid fuel 13 up to the level 14 by a needle valve 15 which is kept constantly supplied with fuel by a liquid fuel line 17. As shown in Fig. 1, the float 16 has a hole 18 extending vertically therethrough.

The cup 11 has a cap 25 having a tubular fuel adjusting valve sleeve 26 extending downwardly axially therefrom through the hole 18, this sleeve 26 having a cylindrical valve seat 27, a fuel hole 28 opening therethrough, internal threads 29 at its lower end, and internal threads 30 of a somewhat larger diameter at its upper end.

Screwed down into the threads 30 is a fuel adjusting screw 35 having a knurled head 36 to facilitate manual operation and a lock spring 37 for holding this screw in any adjusted position. The screw 35 has a valve sleeve 38 which makes a ground fit with the cylindrical valve surface 27 and extends downwardly so that the lower end of the sleeve 38 is adapted to gradually shut off the fuel hole 28 as the screw 35 is screwed downwardly in the threads 30. The screw 35 has a port 39 extending through the wall thereof and a recess 40 is formed in the cap 25 opposite this port, so that this port is at all times connected with the recess 40 which in turn communicates through a port 45 with the chamber 12 and through a hole 46 with a compensating air tube 47. Extending upwardly through an axial hole 50 formed in the floor 51 of the cup 11 and screwing into the threads 29 is a rotor mandrel base 52. This base has a fuel decanting quill 55 extending upwardly to the fuel level 14, the quill 55 passing through a passageway inside this base extending through the lower end of the latter, a rotor mandrel tube 56 being screwed into suitable threads provided therein. The tube 56 has a quill 57 extending upwardly therefrom through the quill 55 and a substantial distance thereabove. Communicating with the space between the quills 55 and 57 are a series of fuel jet orifices 60 so that when fuel rises between the adjusting valve sleeve 38 and the quill 55 to the point above the top of the

latter, this fuel flows downwardly between quills 55 and 57 and out through the fuel jet orifice 60.

The floor 51 of the fuel cup 11 has an irregular bottom surface such as that shown in Fig. 4, which may be produced by radial ridges 65 provided thereon so that the bottom surface of this floor constitutes a pounding block 66, the purpose of which will be made clear hereinafter.

The passageway in the rotor mandrel tube 56 terminates above the lower end of this tube where it connects through a hole 67 with the side of this tube, the lower end of the tube being solid and threaded as shown in Fig. 1. Mounted on the rotor mandrel tube 56 are primary and secondary rotors 70 and 71. Each of these rotors includes a ball bearing 72, these being spaced apart by a sleeve 73 and held upwardly against the mandrel base 52 by a nut 74. On each of the outer races of these bearings, at the lower end thereof, is provided a circular screen 75. Sweat into place on the outer races of the bearing 72 of the rotor 70 is a band 80 having baffle blades 81 which extend radially outwardly and upwardly as shown in Figs. 1, 2 and 5, and are helically bent. It is to be noted in Fig. 1 that, in rotating, the uppermost tips of the baffle blades 81 extend into the line of the fuel ejecting orifices 60.

The outer race of the bearing 72 of the rotor 71 has a band 85 from the upper end of which are formed a series of radially extending baffle blades 86 which are also helically bent as shown in Fig. 2.

The rotors 70 and 71 are disposed in a centrifugal chamber 90 formed by the body 91 of a volute 92 which fits snugly up against the floor 51 of the cup 11 and is provided with a tangential inlet 92 and an axial outlet 94. Provided in the inlet 93 is a choke valve 95. Pressed up against the lower end of the volute 92 and holding this against the cup 11 is a throttle body 96. This body receives the lower end of the rotor mandrel tube 56 and is held in assembled relation with the volute 92 and cup 11 by a nut 97. The throttle body has an idling fuel passage 98 which connects with the hole 67 in the lower end of the tube 56 and leads to an idling nozzle 99, there being an idling adjustment valve 100 also provided in the body 96, this controlling the passage 98. The body 96 provides a fuel vapor passageway 105 which connects at its upper end with the axial outlet 94 in the volute 92. The lower end of this passageway 105 is controlled by a butterfly throttle valve 106.

It is to be noted that the compensating air tube 47 extends downward into the mouth of the tangential volute inlet 93, the object of this being made evident hereinafter.

Operation

In operation, the carburetor 10 is secured by the attaching flanges 110 thereof to the intake manifold of an internal combustion engine with which it is associated. The fuel line 17 is connected to a fuel reservoir so that the needle valve 16 is constantly supplied with fuel, which flows through this valve and fills the float chamber 12 with fuel up to the level 14. Until the engine is started, the fuel remains at this level and none is discharged from the chamber 12. When the engine is spun by the starter, however, the throttle 106 is opened and the choke valve 95 slightly closed thereby causing an excessive vacuum in the centrifugal chamber 90 which is communicated through the orifices 60 and the space between the quills 55 and 57 to

the interior of the fuel adjusting sleeve 38. This vacuum causes an excessive amount of fuel to flow through the hole 28 and upwardly above the level 14 so as to overflow downwardly between the quills 55 and 57 and out through the orifices 60. The spinning of the motor by its starter draws air through the volute inlet 93 so as to rotate the carburetor rotors 70 and 71. Fuel leaving the orifices 60 strikes the baffle blades 81 on the rotor 70, this fuel being broken up by impact with these blades and a certain portion of it deflected against the pounding block 66. A rich mixture of fuel vapor and air is thus produced in the chamber 90 and drawn through the axial opening 94 and throttle valve 106 into the intake manifold of the engine. When the mixture in the cylinders ignites and the engine starts, the choke valve 95 is opened up as the engine now requires a mixture including less fuel and a considerably greater quantity of air. The rate of rotation of the rotors 70-71 then increases substantially and the blades 81 and 86 of these rotors bear the liquid particles of fuel as these are carried around by the swirling mass of air passing through the chamber 90 and breaks these particles up to form a homogeneous mixture of fuel vapor and air. The screens 75 greatly assist in producing this homogeneous mixture, as any particle of fuel engaging these screens when they are rotating tends to adhere to the wires of the screen and by capillary action is spread out so that a very large surface of the liquid in these particles is exposed to the air and the particles are thereby reduced to vapor form.

I have found in actual operation that the carburetor of my invention gives a greatly increased mileage when used on automobiles and also makes possible the use of heavy fuels in high compression automobile and airplane engines, so that these engines can be run at a fraction of the fuel cost now necessary.

While I have shown a volute of just sufficient depth to accommodate two gas beating rotors I contemplate that where the capacity of the engine with which the carburetor is to be used is sufficient to warrant this, a volute of greater depth than that shown in the drawings may be used so as to accommodate a larger number of gas beating rotors.

While I have shown and described only a single embodiment of my invention, it is to be understood that various alterations and modifications may be made in this without departing from the spirit of the invention or the scope of the appended claims.

What I claim is:

1. In a carburetor, the combination of: means forming a float chamber; a float needle valve for feeding fuel to said chamber; a float in said chamber for controlling said valve; a volute disposed beneath said float chamber means and having a centrifugal chamber, a tangential air inlet and an axial air outlet extending downwardly from said chamber; throttle valve means connecting said axial air outlet with the intake manifold of an internal combustion engine; means for conducting liquid fuel from said float chamber and discharging it into the upper end of said centrifugal chamber; and a fuel beating rotor mounted for free rotation in said centrifugal chamber so that said fuel comes in contact with said rotor when it is discharged into said centrifugal chamber.

2. A combination as in claim 1, in which the

floor of said float chamber means provides an upper wall of said volute and has thereon irregular surfaces to constitute a pounding block for breaking up particles of liquid fuel directed there-
5 against by said rotor.

3. In a carburetor, the combination of: a volute having a centrifugal chamber, a tangential air inlet, and an axial air outlet leading down from said chamber; throttle valve means for connecting said axial air outlet to the intake manifold of an internal combustion engine; means for injecting liquid fuel in said centrifugal chamber; a rotor disposed in said centrifugal chamber and responsive to the flow of air therethrough to rotate at a relatively high rate, said liquid fuel coming into contact with said rotor when said fuel is injected into said chamber; and a secondary rotor provided in said chamber between the aforesaid rotor and said axial outlet of said volute, said rotors having helical fan-like blades extending radially therefrom and being independently rotatably mounted in said centrifugal chamber.

4. In a carburetor, the combination of: means forming a mixing chamber having an axis; outlet means through which air may be withdrawn from this chamber along said axis; inlet means through which air is admitted tangentially into the chamber to set up a whirling of the air there-
25 in about said axis; rotor means having fuel beating blades and adapted to freely receive air inwardly through the periphery of said rotor means and permit said air to then flow axially through said rotor means, the latter being mounted in said chamber and freely rotatable about said axis so as to respond to said whirling air in said chamber and rotate therewith, this chamber having a substantial vestibule air space of greater diameter than the balance of said chamber, said air space lying between the periphery of said rotor means and the walls of said chamber and extending substantially around said rotor means, said tangential inlet
30 connecting with said vestibule air space, the latter permitting air introduced through said inlet into said chamber to flow radially inward simultaneously into the interstices of the periphery of said rotor at all points located within a substantial zone of said periphery said zone substantially surrounding said periphery, said rotor means permitting axial movement towards and into said axial outlet of the air thus flowing into said rotor means through the periphery thereof; and means for delivering hydrocarbon fuel into said chamber to permit said fuel and said air to be mixed by said rotor means.

5. In a carburetor, the combination of: means forming a mixing chamber having an axis; outlet means through which air may be withdrawn from this chamber along said axis; inlet means through which air is admitted tangentially into the chamber to set up a whirling of the air there-
10 in about said axis; fuel beating rotor means the axial length of which is substantially greater than the radius thereof and which is adapted to freely receive air inwardly through the periphery of said rotor means and permit said air to then flow axially through said rotor means, the latter being mounted in said chamber and freely rotatable about said axis so as to respond to said whirling air in said chamber and rotate therewith, this chamber having a substantial vestibule air space of greater diameter than the balance of said chamber, said air space lying between the periphery of said rotor means and the walls of said chamber and extending substantially around said rotor means, said tangential inlet
15 connecting with said vestibule air space, the latter permitting air introduced through said inlet into said chamber to flow radially inward simultaneously into the interstices of the periphery of said rotor at all points located within a substantial zone of said periphery said zone substantially surrounding said periphery, said rotor means permitting axial movement towards and into said axial outlet of the air thus flowing into said rotor means through the periphery thereof; and means for delivering hydrocarbon fuel into said chamber to permit said fuel and said air to be mixed by said rotor means.

10. In a carburetor, the combination of: means forming a mixing chamber having an axis; outlet means through which air may be withdrawn from this chamber along said axis; inlet means through which air is admitted tangentially into the chamber to set up a whirling of the air there-
15 in about said axis; fuel beating rotor means the axial length of which is substantially greater than the radius thereof and which is adapted to freely receive air inwardly through the periphery of said rotor means and permit said air to then flow axially through said rotor means, the latter being mounted in said chamber and freely rotatable about said axis so as to respond to said whirling air in said chamber and rotate therewith, this chamber having a substantial vestibule air space of greater diameter than the balance of said chamber, said air space lying between the periphery of said rotor means and the walls of said chamber and extending substantially around said rotor means, said tangential inlet
20 connecting with said vestibule air space, the latter permitting air introduced through said inlet into said chamber to flow radially inward simultaneously into the interstices of the periphery of said rotor at all points located within a substantial zone of said periphery said zone substantially surrounding said periphery, said rotor means permitting axial movement towards and into said axial outlet of the air thus flowing into said rotor means through the periphery thereof; and means for delivering hydrocarbon fuel into said chamber to permit said fuel and said air to be mixed by said rotor means.

WILLIAM O. HADDOCK. 45
